UNITED STATES PATENT OFFICE.

WALTER S. PHILLIPS, OF MEMPHIS, TENNESSEE.

FOLDING HAT-BOX.

1,294,802.

Specification of Letters Patent. Patented Feb. 11, 1913.

Application filed March 15, 1913. Serial No. 14,686.

To all whom it may concern:

Be it known that I, WALTER S. PHILLIPS, a citizen of the United States, residing at Memphis, in the county of Shelby and State 5 of Tennessee, have invented certain new and useful Improvements in Folding Hat-Boxes; and I do hereby declare the following to be a full, clear, and exact description of the invention, such as will enable 10 others skilled in the art to which it appertains to make and use the same.

This invention relates to new and useful improvements in folding hat boxes, and has for its principal object to provide a hat 15 box which is capable of being folded into a small space, which when in its unfolded position is capable of holding a hat to prevent the same from being crushed.

Another object of the invention is to provide a hat box which is particularly adapted 20 for use on shelves in which it is necessary to place articles on top of the hat box so that the user may gain access to the interior 15 of the box without removing the articles on the top thereof.

A further object of the invention is to provide a device which is capable of being applied to crates of all characters or other similar receptacles in which the walls may 25 be hinged.

With these and other objects in view, the invention consists in the novel combination and arrangement of parts which will be fully set forth in the following specification 30 and accompanying drawings, in which—

Figure 1 is a fragmentary perspective view of a box constructed in accordance with this invention, showing the same in 35 its unfolded position.

Fig. 2 is a plan view of the box spread out and completely open.

Fig. 3 is an end view of Fig. 2.

Fig. 4 is a perspective view of the device 40 completely spread out, and

Fig. 5 is a sectional view of the box showing the same folded for shipment.

Referring to the drawings, the numeral 1 designates the bottom of the box having 45 secured to its lateral edges the hinges 2 and 3, one of the longitudinal edges being provided with the hinges 4 to which the end panel 5 of the box is secured. The side panel 6 is secured to the box by means of the hinges 2 and the opposite panel 7 is 50 secured to the box by means of the hinges

3, the top 8 of the box is secured by means of the hinges 9 to the upper edge of the side wall 7 and secured to the end of the top 8 opposite the end wall 5 are the hinges 10 carrying the end wall 11 which forms the front of the box when the device is in use on a shelf.

In order to hold the side walls 6 and 7 parallel and in their vertical position, the eyes 12 are carried by the end wall 5 and coöperate with the hooks 13 carried by the side walls 6 and 7. These hooks are held in place by eyes 14. The hooks 13 are adapted to engage in the eyes 12 as shown in dotted lines in Fig. 3.

It will be evident that the top and front end of the device are open and in order to close the same, the cover 8 is swung on its hinges 9 and the hook 15 carried by the eye 16 in the free edge of said cover is passed through the eye 17 carried by the side wall 6. In order that the front wall 11 may be secured in place, the hook 18 carried by the eye 19 which is secured thereto extends through the eye 20 secured in the end of the bottom 1 and it will thus be seen that a complete box is provided which is designed for the reception of a hat and similar articles of wearing apparel.

From the foregoing it will be evident that to fold the crate into operative position, the wall 7 which normally lies with its inner face to the inner face of the bottom 1 is raised into the position shown in Figs. 2 and 3. The end wall 5 is then moved into the position shown by the dotted lines in Fig. 3 and the hook 13 carried by the side wall 7 engages in an eye 12 carried by the end wall 5. In this way it will be apparent that the wall 7 and end wall 5 will be held securely in the position shown in Fig. 3 by the dotted line, and the wall 6 may then be swung on its hinges 2 until it engages the end of the end wall 5 opposite the wall 7. The hook 13 carried by the wall 6 is then extended through an eye 12 carried by the end wall 5 and it will be apparent that a trough-like structure is thus formed which is open at one end. The cover 8 is then swung on its hinges 9 until the free end engages the upper edge of the wall 6 and the hook 15 then is brought into engagement with the eye 17 and it will be apparent that the whole will form a receptacle in which hats may be placed through the open end. In order to close the open end, the front

wall 11 is swung downwardly on its hinges 10 and the hook 18 carried thereby engages the eye 20 carried by the bottom and it will be apparent that a rigid box is formed upon 5 which articles may be placed without danger of the device collapsing. Should it be so desired suitable strips of felt or a similar fibrous material designated by the numeral 21 may be secured near the edges 10 of the walls 6 and 7 which strips of felt or similar fibrous material prevent dust from accumulating in the box when assembled, and the strip 22 of wood or a similar material to form a stop is secured near the 15 forward edge of the bottom 1. The strip 22 limits the inward movement of the front wall 11 and it will thus be seen that a substantially dust-proof device is provided which will effectively protect the hat from 20 injury.

It is also evident that a box is provided which may be folded and placed in a trunk and when therein will occupy a minimum amount of space. 25 While in the foregoing there has been shown and described the preferred embodiment of this invention, it is to be understood that such changes may be made in the combination and arrangement of parts as 30 will fall within the spirit and scope of the appended claim.

What is claimed is:

In a folding hat box, a rectangular bottom, side walls hingedly secured at their 35 lower edges to the lateral edges of the bottom for movement toward and away from

the same, an end wall hingedly secured to one end of said bottom at its lower edge for movement toward and away from the same, all of said walls corresponding in width, 40 means for detachably securing said side and end walls together so as to hold the same in vertical position, a top wall hingedly secured at one edge to the upper edge of one of said side walls and corresponding 45 in size and shape to said bottom wall, and an end wall hingedly secured to the end of the top wall remote from the end wall secured to the bottom whereby, when all of said walls are disconnected, the top 50 wall and the side wall to which said top wall is hinged may be folded downwardly and inwardly so as to fit snugly on the bottom wall and the remaining side wall and form a compact substantially rectangular 55 article, the end wall secured to the bottom being folded upwardly and inwardly so as to fit snugly against the under face thereof and the end wall secured to the top being folded in an opposite direction downwardly 60 and inwardly so as to lie upon the upper face of said top wall, the whole structure when thus folded being of rectangular outline and relatively thin so as to occupy comparatively little space for shipping purposes. 65

In testimony whereof I affix my signature in presence of two witnesses.

WALTER S. PHILLIPS.
